(57) **CLAIM**

The ornamental design for a rail for shoe upper, as shown and described.

DESCRIPTION

FIG. 1 is a side view of the rail for shoe upper;

FIG. 2 is a top, front perspective view thereof;

FIG. 3 is a top, rear perspective view thereof;

FIG. 4 is a bottom, front perspective view thereof; and,

FIG. 5 is a bottom, rear perspective view thereof.

The broken lines indicate boundaries that form no part of the claimed design. The opposite side of the rail for shoe upper is not shown and forms no part of the claimed design.
